(Cl. D45—4)

To all whom it may concern:

Be it known that I, Charles T. Parisi, a citizen of the United States, residing at 35 Fenwood Avenue, Pawtucket, State of Rhode Island, have invented a new, original, and ornamental Design for an Expansible Bracelet, of which the following is a specification, reference being had to the accompanying drawing, forming a part hereof.

I claim:

The ornamental design for an expansible bracelet, as shown.

CHARLES T. PARISI.
